UNITED STATES PATENT OFFICE.

HARRY BRADSHAW, OF RICHMOND, VIRGINIA, ASSIGNEE TO FREDERICK C. CASWELL,
OF RICHMOND, VIRGINIA.

PAPER-FEEDING MACHINE.

1,209,110.

Specification of Letters Patent. Patented Dec. 19, 1916.

Application filed October 10, 1914. Serial No. 866,127.

To all whom it may concern:

Be it known that I, HARRY BRADSHAW, a citizen of the United States, residing at Richmond, in the county of Henrico and State of Virginia, have invented certain new and useful Improvements in Paper-Feeding Machines, of which the following is a specification.

My invention relates to improvements in paper feeding machines.

The object of my invention is to provide a machine of this character, which is adapted to feed the sheets of paper separately from a pile to a ruling machine or printing press without creasing or otherwise defacing the sheet, and at the same time will insure the sheets being fed in perfect alinement.

Another object of my invention is to provide a machine of this character, in which sheets of any size can be accurately and evenly fed to a machine without the complicated adjustment necessary in the ordinary machine.

A further object of my invention is to provide a machine in which the sheets are lifted from the pile of paper, and positively insures the feeding of the sheets separately from the pile, and thus causes each and all of the sheets to be separately acted upon by the machine to which they are fed.

A still further object of my invention is to provide a sheet feeding machine of this character, which is simple in construction and operation and having certain details of structure and operation hereinafter more fully described.

In the accompanying drawings—Figure 1 is a side elevation of my improved paper feeding machine; Fig. 2 is a front view, looking in the direction of the arrow, Fig. 1; Fig. 3 is a longitudinal sectional view, taken on the line 3—3 of Fig. 2; Fig. 4 is a longitudinal sectional view, taken on the line 4—4 of Fig. 2; Fig. 5 is a longitudinal sectional view similar to Fig. 4, showing the paper holding means, for holding the top sheet when it is being buckled to allow the finger to pass under the same; Fig. 6 is a

similar view to Fig. 5, showing the roller 50 for moving the sheets forwardly to bring them into engagement with the sheet conveying tapes; Fig. 7 is a perspective view of one of the nests carrying the sheet lifting mechanism; and Fig. 8 is a top plan view of the paper conveying tapes, showing them twisted for straightening the sheets, and also showing the guide plate at one side; Fig. 9 is an enlarged top plan view, partly in section, showing the driving means 60 for the rollers.

In feeding devices of this character, the great difficulty has been in separating the top sheet from a pile without defacing it and to absolutely insure the feeding of a single sheet through the machine at one time. Another difficulty has been in providing for the proper pressure upon the pile of paper, when sheets of different sizes are used.

Referring now to the drawings, 1 represents the frame of my improved feeder, which, as shown, is of rectangular form and is adapted to be placed adjacent the ruling machine, or the printing press, and the working parts thereof are adapted to receive their power therefrom, as will be hereinafter more fully described. The frame 1 is formed in two sections 2 and 3, spaced a considerable distance apart and connected 80 together in any desirable manner.

The rear end of each section 2 and 3 is provided with rearwardly extending brackets 4 and 5, in which are mounted the shafts 6 and 7, which extend entirely across the machine. The shaft 7 has mounted thereon the roller 8, over which the sheet conveying belts 20 pass, as will be later described. The upper shaft 6, on the inside of the section 2, is provided with a sleeve 10 loosely mounted thereon and having rigid oppositely extending arms 11 and 12. The lower end of said arm 12 is connected to a forwardly extending rod 13, the purpose of which will be later described. The upper 95 end of the arm 11 has connected thereto the rod 14, which has its outer end connected to a band 15, passing over the pulley 16,

mounted upon the shaft 17 and carried by the brackets 18 mounted upon the sections 2 and 3 of the frame 1. The end of the band 15 is rigidly attached to the frame 1. The forward ends of arms pivoted in sections 2 and 3 are provided with a roller 19, over which passes the endless sheet conveying belts 20, these belts pass rearwardly over the roller 8 and convey the sheets rearwardly to the press or ruling machine. The roller 19 is provided with peripheral grooves 21, in which the conveying belts 20 run, and which prevents any creasing or injury to the sheets of paper as they pass over the roller 19.

Carried by the forward end of the arms on the frame 1, below the roller 19, is a roller 22. Directly above the roller 19, and mounted within the sections 2 and 3, of the frame 1, is a small roller 23, and in the rear thereof, and mounted in the same manner, is a roller 24. Passing around the roller 22 are endless lifting belts 25, which pass upwardly over the roller 19 around the small roller 24 and forward over the upper face of the roller 23 and downwardly to the roller 22, as clearly shown in Figs. 3 and 4 of the drawings. These lifting belts 25 are arranged between the conveying belts 20, as fully shown in Fig. 2 of the drawings.

The table 26, upon which the pile of sheets of paper are stacked, is below the conveying belt 20, and is provided at its outer end with a slightly inclined end plate 27, against which the edges of the sheets of paper rest. This end plate, as shown, is in a vertical line with the outer periphery of the roller 19 and is slightly inclined rearwardly for the purpose of holding the pile of paper with each succeeding sheet with its edge slightly in the rear of the other sheet in order that the lifting finger, hereinafter described, will not engage the sheet below, and, therefore, but a single sheet of paper will be raised from the pile at one operation of the machine.

The sheet lifting mechanism consists of two L-shaped frames 28 and 29, arranged in front of the sections 2 and 3 of the frame 1, and connected together by the rods 30 and 31 at their upper and lower ends and held in their spaced relation by said rods. Directly below the L-shaped frames 28 and 29, the sections 2 and 3 are provided with sprockets 32 and 33, over which the chains 34 and 35 pass. The ends of the chains 34 and 35 are respectively fastened to the bottom of the frames 28, 29, and the said chains pass upwardly over the sprocket wheels 36 and 37, mounted upon opposite ends of the shaft 17. These sprocket chains 34 and 35 pass downwardly and are respectively connected to the upper ends of the frames 28 and 29. By this structure, it will be seen that the sheet raising mechanism is substantially vertically movable.

In order to hold the sheet lifting mechanism in a balanced position, so that the weight at both ends thereof will be equal, I provide the two arms 38 and 39, which have their front ends pivotally connected to the rear end of the sections 2 and 3 of the frame 1. The forward end of these arms are provided with hooks 40, which are adapted to hook in the chains 34 and 35, as clearly shown in Fig. 1 of the drawing. Slidably mounted on these arms 38 and 39 are weights 41 and 42, adjustably held by the set screws 43, whereby the tension of the arms on the chains 34 and 35 is varied by sliding the weights on the arms.

The rod 13 has secured at its outer end a plate 44, carrying a roller 45. Adjacent the plate 44, the sheet lifting frame has mounted therein a shaft 46 carrying a cam 48, provided with a cut-away portion 49, which is adapted to receive the roller 45 to allow the plate 44 to move inwardly to release the brake band 15, whereby the roller 16 is released and the sheet raising mechanism is raised or lowered. This cam is timed with the rest of the mechanism, as will be hereinafter described, so that it will operate at the proper time.

The shaft 46, as heretofore described, is mounted in the L-shaped members forming the sheet lifting mechanism and the rod 50 connects the L-shaped members 28 and 29. Arranged between the L-shaped members of the sheet lifting mechanism, on the shaft 19, the rods 50 and 31 and the shaft 46 are arranged two nests which carry the sheet lifting mechanism proper. These nests are longitudinally movable upon the rods and shafts and are precisely alike, and, therefore, I will describe but one of these nests.

By the longitudinal movement of the nests, it will be seen that they may be brought into such a position that both are working upon the paper and also to bring them in such a position as to work upon paper of different sizes. The lifting tapes and the conveying tapes, as shown in Fig. 2 of the drawings, extend entirely across the front of the machine, so that, no matter in what position the nests are arranged, the tapes will take the paper and convey it upwardly and forwardly to the press or ruling machine, as heretofore described.

The nests are composed of two side members 51 and 52, connected in any desired manner and having the offset portions 53 to extend around the roller 19, over which the sheet conveying tapes 20 pass, and whereby the nests are free to move longitudinally and not interfere with the tapes. Mounted upon the shaft 46, and slidably thereon, but held in its relative position between the plates 51 and 52, is a cam 54 which has a band 55 surrounding the cam and provided with a pitman 55 which extends

downwardly and is pivotally connected at 56 to a link 57 which is pivotally mounted upon the rod 31. Mounted upon the pivot 56 of the pitman 55 are two forwardly extending spaced arms 58 and 59, which have mounted between their forward ends a rectangular shaped member 60. Between the arms 58 and 59, intermediate their ends, is a roller 61 and passing over the roller 61 and over the rectangular shaped member is a rubber belt 62 of an endless form. The rectangular shaped member is so positioned between the arms that it has one of its flat surfaces in a horizontal plane and is adapted to engage the top sheet of a pile of paper and buckle it when moved forward. The endless belt is for the purpose of bringing a new surface to engage the paper. This has been found to be a very marked improvement, as in the old form the roller soon became covered with the very fine lint of the paper and would not take a good hold upon the paper to buckle it. By the rubber belt 62, it will be seen that a greater surface is obtained which will not become covered by the lint in as short a time, and the rubber belt will not become heated by friction with the paper, as a new surface is brought into engagement with the paper on each operation or in so many operations of the paper lifting mechanism. In order to cause this belt to travel around the rectangular shaped member 60, I provide a ratchet 63, mounted upon the shaft of roller 61. Loosely mounted upon the shaft of the roller 61, by slots 61', are the upwardly extending links 64, between which is pivotally mounted the rod 65 rigidly mounted upon the rod 50. One of the links 64 is provided with a pawl 62', which engages the ratchet 63 and when the arms 58 and 59 are moved forwardly through the medium of the pitman 55 and the cam 53, as heretofore described, the links 64 are held against any material forward movement, so that the pawl will travel over the ratchet and upon the backward movement of the arms 58 and 59 the ratchet is rotated carrying with it the roller 61, which causes the belt 62 to move forward and turn the rectangular shaped member 60 to bring another surface in position to engage the paper.

Loosely mounted upon the rod 31 is a forwardly extending arm 66, to which are pivoted the forwardly extending fingers 67 and 68, which are adapted to rest upon the pile of paper, and while I have shown two of these fingers, it will be understood that a single finger could be used, but in actual practice the double fingers have been found to be more practical.

Mounted rigidly upon the rod 50 by set screws is a sleeve 69, which has loosely connected thereto an arm 70, which is normally held in engagement with the cam 71, mount-

ed upon the shaft 46 by means of the springs 72' which has one end secured to a pin 72 carried by the sleeve 69 and the opposite end secured to the hook 70' carried by the arm 70. The lower end of the arm 70 has 70 pivotally connected at 72 the lifting finger 73. This lifting finger is held downwardly upon the finger 67 by means of a spring 74, as clearly shown in Fig. 4 of the drawings. This lifting finger 73 is adapted to be moved 75 inwardly by the cam 71 and after the paper has been buckled, as hereinabove described, and released, the paper is above the lifting finger.

In order to move the paper rearwardly 80 when the lifting finger 73 is moved outwardly, I have provided a friction roller 75, mounted upon the bell crank 76, which is pivoted at 77 to the main frame of the machine. The upper end of the bell crank 76 85 is pivoted to a link 78, and the upper end of said link is pivotally connected to the member 79, which is mounted upon the rod 50 and adapted to rock thereon. Springs 78' are attached to the member 79, so as 90 to hold the same against the cam and hold the roller 75 against the paper. The shaft 46, above the member 79, is provided with a cam 80 which is adapted to force the upper end of the member 79 downward for raising the roller 75 off of the sheet of paper. When the roller 75 is in its downward position upon the sheet of paper, which is resting upon the finger 73, it will be seen that as the finger 73 is drawn outwardly the frictional contact between the roller and the paper will cause the paper to travel upwardly between the endless belt or tapes 20 and 25 and the sheet of paper continues to travel upwardly by contact with the 105 tapes.

The shafts 6 and 7 are provided at each end with sprockets, over which pass the chains 81', and whereby the shaft 7 is driven by the shaft 6. A sprocket chain 110 81' passes over one of the sprockets on the shaft 6 and over a sprocket on the shaft 46. A chain 81 passes from the sprocket on the shaft 7 over a sprocket on the shaft 19. This last mentioned sprocket chain 81 115 drives the roller 24 and is held in engagement with the sprocket on the roller 24 by an idle roller 24'. The belts or tapes 25 are also driven by frictional contact with the roller 19, as will be fully understood by 120 reference to Fig. 4 of the drawings.

The cams 53', 71, 80 and 85 are timed so that the parts operated thereby will work at the proper time, as heretofore described. In order to hold the paper while it is being 125 buckled by the buckling mechanism, heretofore described, I provide the shaft 46 with a cam 85, operating upon a spring pressed rod 86, longitudinally movable in the member 87, which is loosely mounted upon a 130

BEST AVAILABLE COP

4

1,209,110

sleeve on the rod 50. The member 87 is provided with an arm 88, which engages a cam 89, mounted on the shaft 46 and held thereon by the spring 88', whereby the rod 86 is rocked to force it above the pile of paper, the spring 72 withdrawing it. The lower end of the rod 86 is provided with a foot 90, which is adapted to be swung inwardly and downwardly by the cams 85 and 89, and adapted to sustain the weight of the lifting mechanism and to firmly clamp the pile of paper when the buckling mechanism is operated, so that the top sheet of the pile of paper will be buckled, as hereinbefore described.

In this machine, the paper is always worked from one side of the machine. In order to guide the sheets of paper and cause them to travel through the machine and to be delivered to the press or ruling machine in an absolutely straight position, I provide the side of the machine, adjacent the tapes about midway between the front and rear, with a guide 91, as clearly shown in Fig. 8. The frame of the machine adjacent the guide 91 is provided with spirally arranged guides 92, through which the conveying tapes 20 pass and the said guides are so arranged as to cause the tapes 20 to twist on edge and thus throw the sheets of paper toward the guide to cause it to assume a position parallel therewith and thus be fed through the machine in the proper position to be correctly fed to the press or ruling machine. These guides are arranged in three series, A, B and C, each succeeding series being of greater linear extent, thus the tendency to pass or feed the sheets into the guide is as positive on the large sheets to prevent them from being turned too far.

Adjacent the shaft 22 is a square shaft 93 carrying rearwardly extending guides 94, having a bifurcated end through which the belts 25 pass and serve as guides for the same.

Having thus described my invention, what I claim as new and desire to secure by Letters Patent, is:

1. In a paper feeder, the combination with 50 conveying and lifting tapes, a buckling mechanism, a lifting finger adapted to move under the paper after it has been buckled, and a roller adapted to be moved down upon the sheet of paper above the lifting finger 55 and the sheet fed between the conveying and lifting tapes by the backward movement of the lifting finger.

2. In a paper feeder, the combination with 60 conveying and lifting tapes passing around the same roller, a buckling mechanism, a finger adapted to be moved under the sheet of paper after being buckled, a roller adapted to be moved down upon the sheet of paper above the lifting finger, whereby the

outward movement of the lifting finger 65 causes the roller to feed a sheet of paper upwardly between the conveying and lifting tapes.

3. In a feeder, the combination with conveying and lifting tapes passing over the same roller, a buckling mechanism, fingers resting upon the sheet of paper and adapted to turn the edge upwardly after being buckled, a finger adapted to move forwardly below the upwardly turned end of the sheet of paper, and a roller adapted to be brought down upon the sheet of paper above the finger, whereby the outward movement of the finger causes the sheet to travel upwardly between the conveying and lifting tapes.

4. In a feeder, the combination with conveying and lifting tapes, of a horizontally movable buckling mechanism, a finger resting upon the pile of paper and adapted to turn the end of the sheet of paper upwardly after being buckled, a lifting finger movable inwardly below the turned edge of the sheet of paper, and a roller adapted to be brought down upon the sheet of paper above the lifting finger, whereby the outward movement of the lifting finger causes the sheet of paper to travel upwardly between the conveying and lifting tapes.

5. In a paper feeder, the combination with 95 lifting and conveying tapes arranged above the pile of paper, downwardly curved fingers resting upon the pile of paper, a buckling mechanism adapted to engage the top sheet of a pile of paper, means for clamping 100 the pile of paper during the buckling operation, an inwardly extending finger adapted to travel below the buckled sheet, a roller engaging the sheet above the finger, said finger adapted to move the sheet outwardly 105 by the outward movement thereof to bring the sheet upwardly between the conveying and lifting tapes.

6. The combination with a frame, conveying and lifting tapes carried by the frame, 110 vertically movable feeder frames carried by the first-mentioned frame, weighted levers for causing the proper tension on both ends of the feeder frame, and a brake for governing said tension means.

7. In a paper feeder, the combination with 115 a frame, conveying and feeder tapes carried by the frame, vertically movable chains carried by the said frame, a feeder frame carried by the said chain, weighted levers engaging the chains for causing equal tension at each end of the feeder frame, a brake controlling the movement of said chain, and means controlled by the feeding mechanism for controlling the said brake.

8. A paper feeder comprising a frame, conveying and lifting tapes carried by the frame, a paper supporting table below the

115

120

125

tapes, vertically movable chains carried by the ends of the frame, weighted levers engaging the chains for causing an equal tension on the chains, a paper lifting frame carried by the chains, means operated by the tape operating mechanism for operating the lifting mechanism, and means controlled by the lifting mechanism for releasing the

brake controlling the vertically movable chains, substantially as shown and described. 10

In testimony whereof I affix my signature in presence of two witnesses.

HARRY BRADSHAW.
